UNITED STATES PATENT OFFICE.

JOHN ARTHUR DES ROSIERS AND MARTIN W. WEBB, OF EDMONTON, ALBERTA,
CANADA.

SIGNAL.

1,409,135.

Specification of Letters Patent.

Patented Mar. 7, 1922.

Application filed May 11, 1920. Serial No. 320,691.

To all whom it may concern:

Be it known that we, JOHN A. DES ROSIERS and MARTIN W. WEBB, subjects of the King of England, residing at Edmonton, in the 5 Province of Alberta and Dominion of Canada, have invented new and useful Improvements in Signals, of which the following is a specification.

This invention relates to a signaling device for automobiles, and has for its primary object the construction of a device that may be readily operated for giving signals to a following vehicle.

An object of the invention is to provide a 15 device, the movable elements of which will be automatically moved to a displaying position upon the releasing of a catch of simple construction.

Besides the above our invention is distinguished in the manner of constructing the catch so that the parts may be held in inoperative position but upon being released the signaling element will be forced to move to displaying position, and automatically 25 close the circuit of an illuminating device.

With these and other objects in view the invention will be better understood from the following detailed description taken in connection with the accompanying drawings, 30 wherein:

Figure 1 is an elevation of a portion of the wind shield, showing the simplest form of our invention, attached thereto.

Figure 2 is a section view of the device 35 illustrating an automatic circuit closure, and automatic means for forcing the plunger to displaying position.

Figure 3 is an elevation thereof.

Figure 4 is a diagrammatic view of the 40 circuit.

Figure 5 is a section view of a portion of the lamp socket.

Figure 6 is an end elevation.

Figure 7 is a cross section view.

45 In Figure 1 we have shown our invention constructed in the simplest form consisting of a tube 1 secured to the wind shield 2 by clamps 3. Slidably mounted in each end of the tube is a plunger 4 moved to displaying or undisplaying positions by the handle 5 slidably mounted in a slot in the tube. It is of course to be understood that the plunger 4 may have any suitable configuration and may be colored in various manners to 50 attract the attention of the following ve-

hicle. When the signaling device is used at night a bulb arranged in the end of the plunger will be illuminated. In Figure 2 we have illustrated an improved form of our invention over that just described. The 60 tube 6 also has slidably mounted in each end a hollow plunger 7 one end of which is formed into a socket 8. Secured within the plunger is a disk 9 of insulating material having centrally arranged a contact 10 for 65 engagement with the center contact of the bulb 11. Thus it will be seen that one terminal of the bulb is electrically connected to a metallic plunger, while the other terminal abuts the contact 10 which is insulated from 70 the plunger. Held contracted by both plungers when the latter are moved to their positions within the casing is a coil spring 12 of a strength to quickly force a plunger to displaying position upon the releasing of a 75 device now to be described.

Secured to but insulated from the plunger 7 is a catch 13 consisting of a strip of resilient metal having one end formed into contact 14, and its other end formed into a 80 hook 15 which is arranged to automatically snap into engagement with a fiber keeper 16 secured to the casing. A handle 17 of insulating material secured to the catch enables the operator to force the hook 15 out 85 of engagement with the keeper so that the spring 12 may immediately expand and force the plunger to displaying position. Upon the plunger reaching displaying position the contact 14 engages a second contact 18 90 for closing the circuit 19 of the bulb thereof, automatically illuminating the bulb when the plunger is in displaying position. A slot 20 is formed in tube 20 to accommodate the sliding movement of the catch 13. 95

It is of course to be understood that the invention may be constructed in various other manners, and the parts associated in other relations, and therefore I do not desire to be limited in any manner except as 100 set forth in the claims hereunto appended.

What we claim is:—

A signalling device of the character described comprising an elongated tube adapted to be secured upon the windshield of an 105 automobile, an outwardly sprung pressed plunger mounted within each end of the tube, a socket mounted on the outer end of each plunger, an incandescent bulb within each socket, a stationary contact on each 110

22
end of the tube, said contact being connected with one of the terminals of the adjacent incandescent bulb, the other terminal of the incandescent bulbs being grounded, 5 each end portion of the tube being provided with a longitudinal slot extending from said stationary contact toward the center of the tube, a contact carried by each plunger and slideable along said slot, said last named contacts being formed as leaf springs and having their outer ends adapted for engagement with the associated first named con-

tacts, the other ends of said last named contact being formed as catches, finger buttons carried by said last named contacts, and 15 keepers carried by the tube and engageable by said catches for normally holding said plungers in retracted position against the resistance of said springs.

In testimony whereof we affix our signatures.

JOHN ARTHUR DES ROSIERS.
MARTIN W. WEBB.
